[57] CLAIM

The ornamental design for a watch face, as shown and described.

DESCRIPTION

FIG. 1 is a front elevational view of a watch face showing our new design;

FIG. 2 is another front elevational view thereof; and, FIG. 3 is a front elevational view of another embodiment of our new design of FIGS. 1-2 having a digital readout. The broken line showings of various hands in FIGS. 1-3 are for illustrative purposes only and forms no part of the claimed design.
